United States Patent Office

Des. 213,147
Patented Jan. 7, 1969

213,147

STAPLING PLIER OR SIMILAR ARTICLE

John J. Power, Westbury, N.Y., assignor to Swingline,
Inc., Long Island City, N.Y., a corporation of New
York

Filed July 20, 1967, Ser. No. 7,899

Term of patent 14 years

U.S. Cl. D74—1
Int. Cl. D8—02

Fig. 1

Fig. 2

Fig. 3

FIG. 4

FIG. 5

FIG. 1 is a side elevational view of a stapling plier or similar article showing my new design; the side opposite thereto being similar in appearance.

FIG. 2 is a top plan view thereof.

FIG. 3 is a front elevational view thereof.

FIG. 4 is a bottom plan view thereof.

FIG. 5 is a rear elevational view thereof.

I claim:

The ornamental design for a stapling plier or similar article, as shown and described.
